DESIGN FOR WALL-PAPER.

SPECIFICATION forming part of Design No. 12,539, dated October 18, 1881.

Application filed August 25, 1881. Term of patent 3½ years.

UNITED STATES PATENT OFFICE.

EDUARD LEISSNÈR, OF NEW YORK, N. Y., ASSIGNOR TO LEISSNÈR & LOUIS,
OF SAME PLACE.

DESIGN FOR WALL-PAPER.

SPECIFICATION forming part of Design No. 12,539, dated October 18, 1881.

Application filed August 25, 1881. Term of patent 3½ years.

To all whom it may concern:

Be it known that I, EDUARD LEISSNÈR, of New York, in the county and State of New York, have invented a new and original Design for Wall-Paper and Similar Fabrics, of which the following is a specification.

This invention relates to a new and original design for wall-paper and similar fabrics; and it consists in the novel grouping and configuration of parts hereinafter more fully described.

The accompanying photograph illustrates a face view of a wall-paper bearing my new design.

P is a figure resembling somewhat a conventional flower, with projecting leaves. A scroll-like stem, R, projecting from this figure P, contains a larger leaf-like figure, u, below which is another leaf-shaped figure, v, which is at the

left of a larger leaf, t. Below this is a cup-like figure, z, appearing to carry a floral ornamentation, o. A cluster of leaves, s, has on a branch a forked leaf, x. Above this is the figure i, supporting the four-sided figure w. C is a group, from which a leaf, P, appears to grow. All the outlines of the figures mentioned are studiously kept uncertain, so as thereby to produce a peculiar effect.

I claim—

The design for wall-paper, consisting of the figures P, R, C, u, v, t, o, z, s, x, i, and w, substantially as shown.

EDUARD LEISSNÈR.
